UNITED STATES PATENT OFFICE.

JEFFERSON M. SHARP, OF OIL CITY, PENNSYLVANIA.

VALVE FOR PUMPS.

Application filed May 16, 1927. Serial No. 191,753.

My improved valve for pumps is suitable for use with various types of pumps both hand and power-operated, and is designed to meet certain requirements and to possess certain advantages not heretofore possessed by valves of this type, namely:

(1) Simplicity; facility and economy of construction and production, especially in the respect that both the valve and the valve-cage may be formed from bar stock and the forming operations may, in the main be performed upon an automatic screw machine.

(2) Efficiency under heavy and exacting classes of service; comparatively longer life in all classes of service, due to its rugged construction; the ample and accurately aligned guiding surfaces for the valve in its reciprocations, and the fact that the valve proper is invertible or reversible at will with reference to its seat, whereby the valve organization is adapted to render a term of efficient service of substantially twice the length of that rendered by valves heretofore in use.

The construction whereby I am enabled to secure said objects is clearly illustrated in the accompanying drawings in which:

Fig. 1 is a central, vertical section through a valve cage and the adjacent cooperating portion of a pump cylinder, the valve proper being shown in elevation.

Fig. 2 is an elevation of the valve-cage; the lower end in this view being shown as having a screw-threaded end instead of the smooth periphery of the Fig. 1 form.

Fig. 3 is a section on line III—III of Fig. 2.

Fig. 4 is a plan view of one end of the valve.

Fig. 5 is a side elevation of the valve proper.

Fig. 6 is a top view of the valve cage which is given to show a modified form of vent or by-pass.

The construction shown in said drawings is substantially as follows:

The adjacent walls of the pump cylinder, in which my improved valve is mounted are indicated by the reference numeral 1; the outer valve port is supplied with a removable cover 2, which may be secured in position in the usual manner.

The inner valve port 3 communicates with the bore of the pump cylinder. Within said valve ports is mounted a valve-cage which consists of a substantially tubular structure 4, having an open top and through the side

walls of which are formed the ports 5. Said cage is also provided internally, adjacent its lower end, with an integrally-formed valve seat 6. The lower end of said tubular valve-cage is formed for leak-tight insertion into its co-operating inner cylinder port 3, either by means of the smooth tapered periphery 7 or by the screw-thread 7'.

The valve proper Fig. 5, consists of a spool-shaped body having the heads 8.8, which are of identical shape, size and construction, each of which is provided with a chamfered seating edge or face 9.9 for interchangeable, invertible co-operation with said seat 6 within 70 said cage.

A certain portion of the valve, intermediate said heads is cut away as at 10: the diameter of said heads is slightly less than the internal diameter of the cage, whereby said valve is 75 adapted to have free vertical movement therein, and the periphery of each of said heads to have guiding contact with the cage walls as the valve reciprocates vertically therein; thus formed, the valve and cage are provided with 80 large co-operating guiding surfaces which construction materially contributes to and prolongs the efficiency of the valve organization.

For the purpose of causing the valve to 85 seat more quickly than it might otherwise do, a spring 11 may be, if desired, employed, and suitably mounted between adjacent portions of the top of said valve and the cover 2.

For the purpose of providing against a 90 sluggish action of the valve upon account of the presence of fluid, or a tendency to a vacuous condition within the chamber 12, by-pass passages as 13 in Fig. 1, or 14 in Fig. 6, may be provided, and in case the Fig. 6 form 95 of by-pass 14 is employed with a screw-threaded form of cage, said grooves 14 may be employed for the insertion of a wrench for screwing the cage into its service position. A tapped hole 15 may be utilized for 100 grinding the valve to its seat also for removing the valve from the cage.

From the foregoing description it will be readily noted that my improved valve organization consists essentially of a tubular cage, 105 the bore of which is wholly unobstructed by a spider construction of any kind which would cause resistance or obstruction to the flow of fluid through the valve organization is reduced at one end to form an annular shoulder that is adapted as a seat for the valve and that the valve proper consists of a spool-

shaped body both heads of which are adapted to selectively seat upon said cage seat, and that the interior face of the walls of the larger portion of the cage bore and the peripheries 5 of the valve heads are adapted to have guiding contact with each other.

I claim the following:

1. A valve organization for pumps comprising a substantially tubular valve cage 10 having an open upper end, whereby the free insertion and removal of the valve is provided for forming a guide-chamber for the valve and having a valve-seat adjacent the lower end thereof, and a spool-shaped valve each 15 head of which is provided with a seating face, which faces are adapted to interchangeably seat upon said valve-seat; the peripheries of said heads being adapted to have guiding contact with the inner walls of said cage.
2. A valve organization for pumps comprising a substantially tubular valve-cage having an open, unobstructed upper end whereby free access to and removal of the valve is provided for, the upper portion of 25 which is provided with ports and forms a guide-chamber for the valve, the lower portion of said chamber being provided with an

inwardly projecting valve-seat, and a spool-shaped valve the heads of which are provided with seating faces adapted to interchangeably seat upon said valve-seat; the peripheries of said heads being adapted to have guiding contact with the inner walls of said cage.

3. A valve organization for pumps comprising in combination with a carrying structure comprising a portion of the cylinder of a pump provided with a tapered port for the reception of a correspondingly-formed portion of a valve-cage, a substantially tubular 40 valve-cage having a portion thereof formed to seat leak-tight in said tapered port, a valve-seat formed within and adjacent the lower end of said cage, and a spool-shaped valve having its heads formed to reversibly and interchangeably seat upon said seat with the peripheries of said heads in guiding contact with the inner walls of said cage; the bore of said cage being unobstructed and the upper end thereof open, whereby ready removal, inversion and reinsertion of the valve 45 is provided for.

In testimony whereof I affix my signature.
JEFFERSON M. SHARP.
